CLAIM

The ornamental design for a cable organizer as shown and described.

DESCRIPTION

FIG. 1 is a top perspective view of a cable organizer showing my design;

FIG. 2 is a bottom perspective view, thereof;

FIG. 3 is a left end elevation view, thereof, the opposite side being a mirror image;

FIG. 4 is a left end perspective view, thereof.

FIG. 5 is a top plan view, thereof.

FIG. 6 is a right side elevation view, thereof, the opposite side being a mirror image; and,

FIG. 7 is a bottom plan view thereof.

The cable organizer is intended to be used for organizing cables inserted through the left side opening of the end elevation view of FIG. 3.
